UNITED STATES PATENT OFFICE.

LULA M. WOBST, OF MILWAUKEE, WISCONSIN.

SIFTER.

Application filed April 4, 1922. Serial No. 549,642.

To all whom it may concern:

Be it known that I, LULA M. WOBST, a citizen of the United States, and resident of Milwaukee, in the county of Milwaukee and State of Wisconsin, have invented certain new and useful Improvements in Sifters; and I do hereby declare that the following is a full, clear, and exact description thereof.

The invention relates to sifters of a type adapted to feed material, such as flour, through a series of screens.

It comprises a plurality of sifter sections each provided with a screen and nested in a lower section, agitators operable on the rotation of a knob to stir the material being sifted, and locking devices, whereby the sections are secured to each other and readily released.

A primary object of the invention is the ready assembly and locking together of the diverse sifter sections and parts and the facile removal of the sections for cleaning. Each of the sections is provided with a bayonet joint, whereby it cooperates with other sections. The handle has a pair of flanges which cooperate with ears on each section so that the handle may be readily and conveniently slipped into place where it will hold the sections in rigid relationship.

An additional object of the invention is the provision of a longitudinal deformation on a rod rigid with the handle, the deformation being adapted to grip the ears of the sifter sections, thus preventing the handle from accidentally sliding with respect to the sections and permitting the carrying of the entire sifter about on the handle without danger of release of any of the sections.

An object of the invention is the convenient association of a screen with its sifter section, the section being merely crimped to grip a flange on the screen.

Additional objects are simplicity of construction and ease of manufacture. The device is, also, thorough in its operation as the portable sections cooperate with the agitating spiders to completely remove the undesirable particles from the material sifted.

With the above and other objects in view, which will appear as the description proceeds, my invention resides in the novel construction, combination and arrangement of parts, substantially as hereinafter described and more particularly defined by the appended claims, it being understood that such

changes in the precise embodiment of the herein disclosed invention may be made as come within the scope of the claims.

In the accompanying drawing, I have illustrated one complete example of the physical embodiment of the present invention constructed according to the best mode I have so far devised for the practical application of the principles thereof, and in which:

Figure 1 is a horizontal section on the line 1—1 of Figure 2.

Figure 2 is a side elevation of the invention, the upper part being shown in vertical central section.

Figure 3 is a detail of the lot.

The various sifter sections are of similar shape, but body portion 10 of the lower sections is of slightly different construction from body portion 11 of the topmost section. Body portions 10 are provided with an L-shaped deformation 12 adjacent the upper peripheral bead 13 adapted to receive a boss 14 on the sleeve 16 of the sifter section immediately above. The body portion 10 is of slightly greater diameter than the sleeve 16 and at 17 is crimped upwardly to form a fold or loop 18 which receives the depending flange 19 of screens 20 so that the screens are held rigidly in position. This manner of association of screen and sifter section is convenient to make and simple in nature.

From fold 18 the metal is directed downwardly at 21 forming sleeve 16 which terminates in an inwardly directed bead 22. Body portion 11 is not provided with an L-shaped deformation, but terminates in circumferential bead 23 and supports a spanner 24 having a central boss 25 through which a vertical rod 26 is directed, the rod being integral with arm 27 carrying knob 28. The rod is square in cross section and passes through openings in screens 20 which are protected by an eye 29 and a washer 30 held in position by flange 31 directed outwardly from the eye. The eye serves to reinforce the screens at this point, protecting them from abrading action.

Agitators 32 have a plurality of arms 33 provided with central, longitudinal, downwardly directed deformations 34. The agitators are provided with a central opening receiving rod 26 and are protected by an iron reinforcement 35 having a square opening so that the reinforcement and agi-

tator fits snugly between rod 26 and on the rotation thereof, the agitator is moved causing deformation 34 to scrape along screen 29 and stir the flour or other material which is being subjected to the sifting operation. The flour drops from one screen to another and is more thoroughly sifted as it approaches the lowermost sifter section.

Each of the sifter sections is provided with a pair of ears 36, the arms 37 of which are downwardly directed and receive longitudinal flanges 38 directed inwardly from rod 39 to which handle 40 is secured.

In assembling the parts, each sifter section is nesting in a lower sifter section, the boss 14 being moved downwardly and engaged in deformation 12 by the rotation of sifter sections with respect to each other, the connection being a bayonet joint. The ears 36 are then alined and rod 39 is moved up by manually gripping handle 40 and flanges 38 are slid into position engaging one pair of ears after another. The entire device is then in assembled relation. Rod 39 is provided with a longitudinal corrugation 41 which contacts with arms 37 of ears 36 and maintains a tight frictional engagement therewith so that the entire sifter may be lifted by handle 40 and carried from place to place. Rod 26 is assembled with respect to the sifter sections by being merely threaded through the openings in boss 25, the agitators 32, and eyes 29.

I claim:

1. In a sifter, the combination of a plurality of sifter sections, ears on said sections, a handle, and slideable means cooperating with said handle and said ears for locking said sections together.

2. In a sifter, the combination of a plurality of nesting sifter sections, deformations on said sections for locking said sections together, ears on said sections, a handle, and means cooperating with said ears for locking said sections together.

3. In a sifter, the combination of a plurality of sifter sections, said sections being nested together, deformations in said sections for securing said sections together, a plurality of ears, a handle, and slideable means cooperating with said ears and said deformations to lock said sections together.

4. In a sifter, the combination of a plurality of nesting sifter sections, a screen for each of said sections, a plurality of spiders having apertures therein, arms on said spiders, longitudinal deformations in said arms, said spiders having openings therein, and a rotatable rod extending through said openings for moving said spiders over said screens.

In testimony that I claim the foregoing I have hereunto set my hand at Milwaukee, in the county of Milwaukee and State of Wisconsin:

LULA M. WOBST.
